(57) **CLAIM**

The ornamental design for a knife block, as shown and described.

DESCRIPTION

FIG. 1 is a top, front, right-side, perspective view of a knife block;

FIG. 2 is a bottom, front, left-side, perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a vertical cross-section view taken along line 9-9 of FIG. 6 thereof; and,

FIG. 10 is a vertical cross-section view taken along line 10-10 of FIG. 6 thereof.

The broken lines shown in the drawings depict portions of the knife block that form no part of the claimed design.

1 Claim, 7 Drawing Sheets
